UNITED STATES PATENT OFFICE.

CHARLES E. HOOVER, OF STRASBURG, PENNSYLVANIA.

PACKAGE-TIE.

No. 903,722.

Specification of Letters Patent. Patented Nov. 10, 1908.

Application filed October 7, 1907. Serial No. 396,289.

To all whom it may concern:

Be it known that I, CHARLES E. HOOVER, a resident of Strasburg, in the county of Lancaster and State of Pennsylvania, have invented certain new and useful Improvements in Package-Ties; and I do hereby declare the following to be a full, clear, and exact description of the invention, such as will enable others skilled in the art to which it appertains to make and use the same.

My invention relates to an improvement in package ties,—the object of the invention being to provide a simple and efficient device constructed of a single piece of wire, and adapted to receive and securely hold the respective ends of a cord without necessity of wrapping the latter around any part of the device.

A further object is to so construct the device that it will properly retain its position upon a package.

With these objects in view the invention consists in certain novel features of construction and combinations of parts as hereinafter set forth and pointed out in the claim.

In the accompanying drawings Figure 1 is a view illustrating my improvements when applied to a package. Fig. 2 is an enlarged detail view of the device, and Fig. 3 is a view showing the device provided with a hand hold.

1 represents a piece of spring wire, the ends of which are first bent upon themselves and the double strands of wire thus formed are bent laterally to form arms 2, 2,—the arm 2 at one end of the device projecting in the opposite direction from the arm 2 at the other end thereof. These arms serve to retain the device flat upon a package.

At each end of the device, the free end of the wire forming one of the double strands

is bent and forms a loop 3,—the members 4—5 of said loop lying at respective sides of the body-portion 1 of the device and the 45 portion of the loop connecting said loop-members being disposed over said body-portion 1. From this construction and arrangement of parts, it will be seen that when the device is placed upon a package, it will be 50 in position to receive the respective ends of a cord 6 passing around the package,—the ends of said cord being passed under the loops 3 and the members of said loops (being disposed at respective sides of the body 55 wire 1) will clamp the cord tightly against said body wire and thus securely hold the same against possibility of slipping.

If desired, the body-portion of the device may be increased—somewhat in length, and 60 bent to form a hand-hold 7, as shown in Fig. 3.

Having fully described my invention what I claim as new and desire to secure by Letters-Patent, is,—

A device of the character described, comprising a single piece of spring wire having each of its end portions bent laterally forming arms projecting in opposite directions at respective ends of the device, the free ends 70 of the wire being bent to form loops disposed over the intermediate body portion and through which said body portion passes, the members of each loop cooperating with the body portion between them to form a 75 cord clamp.

In testimony whereof, I have signed this specification in the presence of two subscribing witnesses.

CHARLES E. HOOVER.
